DESIGN FOR AN ELECTRIC GRILL ASSEMBLY UNIT

Joseph Sedlack, Cleveland, Ohio

Application November 27, 1937, Serial No. 73,227

Term of patent 7 years

To all whom it may concern:

Be it known that I, Joseph Sedlack, a citizen of the United States, residing at Cleveland, in the county of Cuyahoga and State of Ohio, have invented a new, original, and ornamental Design for an Electric Grill Assembly Unit, of which the following is a specification, reference being had to the accompanying drawing, forming part thereof.

In the drawing, Fig. 1 is a perspective view of an electric grill assembly unit embodying my invention and showing the upper heating portion

in open position and with a removable cover positioned on the base; Fig. 2 is a perspective view of the article illustrating the heating element in closed position on the base; Fig. 3 is an end view of the article in the position illustrated in Fig. 2, and Fig. 4 is a section taken on the line 4—4 in Fig. 2.

I claim:—

The ornamental design for an electric grill assembly unit as shown.

JOSEPH SEDLACK.
